UNITED STATES PATENT OFFICE

99,865

DESIGN FOR AN EYECUP

Carl G. Hilgenberg, Baltimore, Md., assignor to
Carr-Lowrey Glass Co., Baltimore, Md.

Application April 17, 1936, Serial No. 62,176

Term of patent 14 years

To all whom it may concern:

Be it known that I, Carl G. Hilgenberg, a citizen of the United States, residing at Baltimore, in the State of Maryland, have invented a new, original, and ornamental Design for an Eyecup, of which the following is a specification, reference being had to the accompanying drawing, forming part thereof.

Figure 1 is a front elevation of an eyecup showing my new design.

Figure 2 is a side elevation thereof.

Figure 3 is a top plan view.

I claim:

The ornamental design for an eyecup, as shown.

CARL G. HILGENBERG.
